(57) **CLAIM**

The ornamental design for a coaxial connector, as shown and described.

DESCRIPTION

FIG. 1 is a top right front perspective view of the coaxial connector;

FIG. 2 is a bottom left rear perspective view of the coaxial connector;

FIG. 3 is a bottom right front perspective view of the coaxial connector;

FIG. 4 is a front elevation view of the coaxial connector;

FIG. 5 is a rear elevation view of the coaxial connector;

FIG. 6 is a top plan view of the coaxial connector;

FIG. 7 is a bottom plan view of the coaxial connector;

FIG. 8 is a left side elevation view of the coaxial connector;

FIG. 9 is a right side elevation view of the coaxial connector;

FIG. 10 is an enlarged partial view of the coaxial connector defined by boundary lines shown in FIG. 2;

FIG. 11 is an enlarged partial view of the coaxial connector defined by boundary lines shown in FIG. 3;

FIG. 12 is an enlarged partial view of the coaxial connector defined by boundary lines shown in FIG. 7;

FIG. 13 is an enlarged partial view of the coaxial connector defined by boundary lines shown in FIG. 7;

FIG. 14 is an enlarged partial view of the coaxial connector defined by boundary lines shown in FIG. 7; and,

FIG. 15 is a top right front perspective view of the coaxial connector, in an environmental state.

The Dash-Dash broken lines depict environmental structure and portions of the coaxial connector that form no part of the claimed design. The Dash-Dot broken lines shown in FIGS.

(Continued)

2-3, 7, and 10-15 depict environmental structure and the boundaries of the enlarged partial views that form no part of the claimed design.

1 Claim, 15 Drawing Sheets
